(57) **CLAIM**

The ornamental design for a personal computer, as shown
and described.

DESCRIPTION

This application is related to U.S. Design patent application
for Personal Computer of Peter K. Lee, Kenneth D. Wood,
and Jeffrey A. Salazar (application No. 29/121,612) filed on
the same date as this application which is hereby incorpo-
rated by reference for all that it discloses.

FIG. 1 is a top, front, right perspective view of a personal
computer showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a detailed cross sectional elevation view of the
front lower portion thereof illustrating details of the front
bezel and a recessed portion of the front panel positioned
proximate the lower tip of the front bezel and taken along
line 8—8 in FIG. 2.

The broken lines are shown in the views for illustrative
purposes only and form no part of the claimed design.
